TUNNEL LINER

Robert V. Proctor, Youngstown, Ohio, assignor to
The Commercial Shearing & Stamping Com-
pany, Youngstown, Ohio, a Corporation of Ohio

Continuation of application Serial No. 367,729,
June 1, 1929, and in Great Britain July 23,
1930. This application May 26, 1931. Serial
No. 540,149

24 Claims. (Cl. 61—45)

This application is a continuation of my co-pending application, Serial No. 367,729, filed June 1, 1929, for Liners.

My invention relates to liners, and more particularly to tunnel liners.

One manner of advancing tunnels, where soft earth is encountered, is that of forcing a shield into the earth ahead of a series of abutting, circular courses of a metallic tunnel liner. The 10 shield, which has a cross sectional shape corresponding to the shape of the finished tunnel and which is slightly larger than the tunnel liner, is provided with a tail which overlaps a portion of the completed liner. The shield is advanced by interposing jacks between the forward course 15 of the completed portion of the tunnel liner and the shield, and extending the jacks as earth is removed from in front of the shield.

After the shield is advanced a distance at least 20 as great as the width of a liner course, the jacks are retracted and a new course is put in position. The jacks are thereafter placed in engagement with the newly completed course, preparatory to again advancing the shield a distance 25 corresponding to the width of a course.

The courses are each made up of a plurality of segments connected to form circumferentially extending bands or rings, which withstand circumferential forces applied to the tunnel by the 30 surrounding earth and forces set up by the shield.

I have invented a tunnel liner segment for withstanding the forces exerted by the jacks as the shield is advanced. According to the invention, liner segments are provided with thrust 35 members extending between the side edges of the segments longitudinally of the tunnel. The forces exerted against the forward course of a tunnel liner as the shield is advanced are of considerable magnitude. The longitudinal forces 40 applied to any particular course are reduced as the tunnel progresses beyond that course so I provide transverse thrust members which may be temporarily inserted in the courses for subsequent removal. Other thrust members are permanent parts of the segments and remain in the finished tunnel liner.

According to the invention, furthermore, individual segments are made up of sheet metal bent to form a rear wall for the segment, which 50 serves as the outer wall or skin plate of the liner, and side sections extending at substantially right angles to the rear wall. Curved sections are formed between the side walls and the rear wall. Reinforcing or thrust members are disposed along 55 the rear wall of each segment with their ends

bearing against the opposite side walls of the segment in a direction longitudinally of the tunnel. However, the curved portions of the segments at the bases of the side walls, if allowed to remain in their natural positions, necessitate 60 the cutting back of the ends of the thrust members at the side walls. As the rigidity of the tunnel liner as a whole depends upon the absorption of longitudinal forces by successive courses rather than by the first few courses in the tunnel, 65 it is desirable that the side walls of each segment firmly engage the ends of the thrust members, which are usually of standard metal shapes, herein illustrated as I-beams.

To provide a substantially flat engaging face 70 between the ends of each thrust member and the cooperating side walls, the curved portions of the segment are offset laterally relative to the major portion of the rear wall of each segment. Preferably the curved portions are offset rearwardly 75 of the segment or outwardly of the tunnel liner. With this construction, the major portion of one of the surfaces of each thrust member engages the rear wall of the segment, and the ends bear against substantially flat side walls of the segment so that forces applied externally of the 80 side walls are transmitted directly to the thrust members without material distortion of the segments.

Where the segments are distorted, difficulty is 85 had in keeping the tunnel alignment and in preventing the leakage of water and fine earth through the tunnel liner. If the tunnel is of considerable length, the cumulative effect of such leakage may prove considerable unless care is 90 taken to insure a good joint as each segment is added to the previously completed tunnel liner. The present structure is particularly adapted for use with tunnels of large size.

Where the tunnels are built along curves, difficulty has heretofore been experienced in properly curving the tunnel liner. In order to better enable the tunnel liner to follow curved tunnels, I provide courses which are tapered, in that they 95 are wider on one side than at a diametrically opposite point. By inserting the tapered courses between those of regular size and shape, it is possible to cause the tunnel liner to conform to curves without requiring the use of an excessive 100 number of specially shaped sections.

The accompanying drawings illustrate certain 105 present preferred embodiments of the invention, in which

Figure 1 is a longitudinal plan view of a portion of a curved liner.

Figure 2 is a broken perspective view of a liner segment,

Figure 3 is a similar view of a tapered segment,

Figure 4 is a broken longitudinal sectional view 5 of a segment in the position it normally occupies in an assembled liner,

Figure 5 is an end view of a liner segment, partially in elevation and partially in section,

Figure 6 is a fragmentary circumferentially 10 extending sectional view of a pair of sections of standard size, and an intermediate connecting section of reduced size,

Figure 7 is a view similar to Figure 4 showing 15 temporary, longitudinally extending, reinforcing members secured intermediate the permanent reinforcing members,

Figure 8 is a perspective view of a portion of 20 a tunnel liner illustrating a method of closing the seams between adjacent plates,

Figure 9 is a cross sectional view thereof taken 25 along the section line IX—IX of Figure 8,

Figure 10 is a sectional view through a circumferential reinforcing rib taken along the section line X—X of Figure 8,

Figure 11 is a cross sectional view of a circumferentially extending reinforcing rib showing another method of closing the joint,

Figure 12 is a similar view of another form 30 of joint, and

Figure 13 is a similar view of a further modification of the invention.

Referring to the drawings, a tunnel liner 2 comprises a series of courses 3, each of which is composed of a plurality of segments 4 of substantially rectangular shape. The edges of the segments in the courses 3 are secured together to form circumferentially extending reinforcing ribs within the tunnel liner, which ribs withstand lateral pressures applied to the liner. For 35 changing the direction of the tunnel, tapered courses 6 comprising tapered segments 7, of different widths, are inserted between the courses 3. By disposing the tapered courses 7 intermediate groups of courses 3 comprising plates 4 of regular shape, the direction of the tunnel can be shifted, as shown by the dotted lines in Figure 1, without requiring specially shaped segments for each course, thereby resulting in a material economy in the cost of the segments used.

Referring to Figures 2, 4 and 5, each segment 4 comprises sheet of metal bent to form a skin plate, rear wall, or body section 8, and laterally extending sections 9 constitute side walls for the segment. Preferably the side walls 9 are bent 55 at substantially right angles to the plane of the rear wall 8, although it is to be understood that for certain purposes the angle of inclination of the side walls to the rear wall may be varied. The rear wall 8 of each segment constitutes a portion of the outer wall of the tunnel liner when the liner is assembled. The sections 8 and 9 are connected by curved, offset sections 10.

For transmitting forces longitudinally of the tunnel, reinforcing or thrust members 11, illustrated in the form of I-beams, are secured by welds 12 to the inner face of the rear wall 8 with considerable portions of the outer face of each beam in engagement with the inner face of the rear wall 8. The ends of the reinforcing members 11 are cut square to meet the substantially flat faces of the side walls 9.

If it were attempted to bend the side walls 9 upwardly from the plane of the rear wall 8, the fillet which would inevitably be formed would interfere with a close fit between the reinforcing

members 11, the side walls 9 and the rear wall 8. A corner at each end of the reinforcing member would have to be cut away to permit the desired close fit, or else the reinforcing member would have to be spaced so far from the rear wall 8 as to lose the rigidity imparted to the segment by the engagement therewith of the reinforcing members 11.

By offsetting the bent sections 10 relative to the plane of the rear wall 8, as by dishing in the latter, the obstructing fillets are displaced laterally of the plane of the rear wall. With this construction, the surfaces of the several reinforcing members 11 engage substantially flat surfaces of the rear wall 8 for considerable lengths, and the side sections 9 present substantially flat surfaces to the ends of the reinforcing members.

When the segments are placed in courses, the reinforcing members 11 of the successive courses cooperate to distribute longitudinal strains, such as are imposed by the jacks in advancing the shield at the head of a tunnel, over a considerable number of courses instead of concentrating such forces at the foremost courses. Where excessive pressures are concentrated on the foremost courses danger of deforming the courses exists, with a subsequent liability to leakage at the seams.

The ends of the segments 4 are closed by end walls formed of flat pieces 14, which are secured in any suitable manner as by internal welds 15 to the ends of the side walls 9. Angle irons or other reinforcing means 16 extend longitudinally of the segments 4 near the outer edges of the walls 9, to which they are secured as by welds 17. The legs of the angle irons 16 engaging the side walls 9 may abut the upper surfaces of the thrust members 11, to which they may be secured by welds 18. Other welds 19 secure the angle-iron flanges to the inner surfaces of the side walls 9. The side walls 9 and end walls 14 are provided with openings 20 and 21, respectively, for the reception of clamping bolts 22, or other securing means such as rivets, when the segments are assembled to form courses whereby adjacent 105 courses are secured to each other.

The angle irons 16 and side walls 9 are preferably placed circumferentially of a tunnel liner so that they constitute reinforcing ribs between adjacent courses. Openings 23 in the skin plates 110 of segments 4 are provided for feeding grout outside of the finished tunnel liner. Tie plates 24 may be attached to the segments 4 for connecting them to adjacent segments.

Referring to Figure 6, a key segment 25 is provided for completing each course of the tunnel liner. The several key segments 25 have end walls inclined so as to taper toward the exterior of the liner. After a number of segments 4 of regular size are in position, a slightly shorter segment is added having an inclined end wall 14a. The key or wedge segment is then forced into the space remaining open in the course. By providing a tapering wedge or key segment, the course is caused to take its proper shape by the application of an expanding force in an arc of the liner, as distinguished from expanding the course by applying jacks along chords of the liner. By using a key or wedge segment for completing the course, great accuracy in the final shape of the tunnel 135 liner is obtained.

As the longitudinal forces in the tunnel liner are greatest near its forward end during the advancement thereof, it is possible to utilize a number of permanent reinforcing members 11 to carry the 150

load on the finished tunnel liner and to supply additional temporary reinforcing members 27 during the construction of the tunnel liner. The temporary reinforcing members are disposed between the rear walls 8 of the segments and the flanges of the angle irons 16. However, instead of being welded to the wall of the segment and to the angle irons, temporary supporting and wedging blocks 28 are driven between the second flanges of the angle irons and tops of the reinforcing members, as shown in Figure 7. Certain of the details of the construction and operation of temporary reinforcing members are shown and described in U. S. patent to Cushwa, No. 1,843,102, granted January 26, 1932.

The segments constituting the tapered courses 6 are substantially similar to the segments 4, as shown in Figure 3, except that the lengths of the reinforcing members 11 decrease progressively in a direction longitudinally of the segments, and the walls 14' of the segments are of different lengths, as illustrated in Figure 3. It is to be understood, however, that only one pair of segments 7 having the same dimensions are used in any one course 6. Such segments are preferably placed at opposite positions in the course at the ends of chords perpendicular to the plane in which the tunnel is to be curved. Successive pairs of such opposite segments vary in size in accordance with their positions in the tunnel liner. By shifting the relative positions of the segments of maximum and minimum width in any tapered course 6, the direction of the tunnel liner may be shifted horizontally, vertically, or at an intermediate angle as desired.

For preventing seepage of water between adjacent segments and courses, I may utilize any one of a number of different constructions. In Figure 6 gaskets 30 are shown between the walls 14 and 14a of adjacent plates. It is to be understood that similar gaskets may be utilized between adjacent end walls 9 if desired.

Where the dimensions of the tunnel liners are considerable, I prefer to positively seal the joints between the segments by metallic or other caulking substances in preference to the use of gaskets.

Figures 8, 9 and 10 illustrate one manner of closing such joints. Segments 31 are provided along their integral side walls 32 with angle irons 33, corresponding to the angle irons 16, which have legs 34 extending beyond the ends of the walls 32. The legs 34 on adjacent segments are curved outwardly beyond the ends of the walls 32 so that a pocket 35 is formed between the ends of the walls 32 and overhanging shoulders 36 on the angle irons 33. The pockets 35 are filled with intermittent welded beads 37 connecting the walls 32 and around which waterproofing material 38, such as lead, oakum, or the like, is packed.

As shown in Figures 9 and 10, substantially the same pocket joint construction is used for the integral side walls 32 of the plates, as shown in Figure 10, and for the welded end walls 39, shown in Figure 9. Each wall 39 comprises a plate 39a and a re-enforcing angle iron 39b shaped to provide a portion of a pocket 40 for caulking material. Intermittent or continuous welds 37 connect the plates 39a and angle irons 39b, thereby preventing spreading when the caulking material is inserted. The walls 32 and 39 are illustrated as being secured together by bolts 41 which are surrounded by grommets 42. It is to be understood, however, that rivets may be substituted for the bolts 41, in which case the grommets are

not needed. The grommets 42 are preferably of lead. The forces applied to the segments are considerable and a durable metallic joint is needed to prevent leakage through the bolt holes. In the case of rivets, the holes in the walls are closed by the rivet heads.

Referring to Figure 11, where segment walls 44 extend beyond the adjacent reinforcing flanges 45, the joints between the segments 44 and 45 may be made by continuous or intermittent welds 46 and the joint between the walls 44 is closed by a continuous weld 47. Rivets 48 hold the walls 44 together. The welds 46 and 47 may merge into each other, if desired.

Referring to Figure 12, I have illustrated a modification of the invention in which segment walls 49 and 50 are of unequal lengths. The wall 49 extends outwardly beyond an attached angle iron 51 and beyond the end of the wall 50. A continuous or intermittently welded bead 52 connects the wall 49 and angle iron 51. A similar bead 54 connects the wall 50 and an angle iron 55. A caulking tool 56 is used for closing the joint between the walls 49 and 50 by driving an edge 57 of the wall 50 against the outer surface of the wall 49.

In Figure 13 I have illustrated a form of the invention in which a straight side wall 58 is secured to an angle iron 59 by a welded bead 60. A side wall 61 on an adjacent segment is provided with an offset portion 62 which cooperates with a corresponding offset portion 64 of an angle iron 65 to which it is secured by a welded bead 66. The space between the side wall 58 and the offset portion 62 of the wall 61 is filled with caulking 67, such as lead, oakum or the like.

While I have shown rivets 48 connecting the side walls of the plates in the forms of my invention shown in Figures 11, 12 and 13, it is to be understood that bolts and grommets, similar to those shown in Figures 8, 9 and 10 may be used if desired. The presence of the bolts and/or rivets connecting the walls of adjacent segments holds the segments in close alignment and cares for reverse strains, such as sometimes occur in tunnel liners and which might tend to separate the plates.

While I have shown and described the present preferred embodiment of my invention, it is to be understood that it may be otherwise variously embodied without departing from the spirit of the invention or the scope of the appended claims.

I claim:

1. A liner segment for earth borings comprising a skin plate having side walls bent at an angle thereto, a thrust member extending along the inner surface of said skin plate abutting said walls, and curved portions connecting the side walls and the skin plate and being offset relative to the latter.

2. A liner segment for underground passages comprising a dished rear wall, integral side walls and connecting curved portions, and a thrust member extending along the inner surface of said rear wall and engaging said side walls, said curved portions being offset relative to the major portion of the rear wall, in such manner that the thrust member engages a smooth surface of considerable area at the rear wall and engages substantially flat surfaces of the side walls at the ends thereof.

3. A liner segment for underground borings comprising a skin plate having side walls bent at an angle thereto, a thrust member extending along the inner surface of said rear wall and en-

gaging said side walls, curved portions connecting said skin plate to said side walls and being offset relative to said skin plate whereby the walls and plate present substantially flat faces to said thrust member, and means for closing the ends of the segment.

4. A tunnel liner segment comprising a skin plate, side walls integral therewith, and curved sections lying outside the plane of the skin plate 10 connecting the plate and side walls.

5. A tunnel liner segment comprising a skin plate, integral side walls extending at an angle to the plate, curved sections lying outside the plane of the plate connecting the plate and the side walls, and plates secured to the ends of the skin plate and side walls, to form end walls for the completed liner segment.

6. A tunnel lining subject to axial thrust during construction, comprising a plurality of rings, 20 each formed of a plurality of wrought metal segments, each segment being composed of a skin plate, side walls for the segment of substantially equal depth extending inwardly of said skin plate, reinforcing means extending longitudinally of both the side walls and projecting at an angle therefrom and equally spaced from the skin plate, the skin plate, side walls and reinforcing members for both the latter constituting a unitary structure, and transverse members for the segment 25 engaging said side walls to sustain said thrust, said members being so positioned in the segments that when the segments are disposed in adjacent rings, the members are in substantial alinement, and effective to remove the thrust load 30 in part, at least, from the skin plates.

7. A tunnel liner segment comprising a skin plate, side walls therefor of equal depth, both side walls having means equally spaced from the plate projecting inwardly thereof to increase the section modulus of the segment, and to resist transverse deflection of the side walls between points of attachment when two segments are secured together side by side, said skin plate, side walls, and the modulus-increasing means for both the latter 45 constituting a unitary structure, and thrust members extending across the skin plate, engaging the side walls, and disposed so as to be in substantial alinement with similar members in segments positioned laterally adjacent thereto in a tunnel lining, providing ribs axially of the tunnel for resisting the axial thrust to which the lining may be subjected.

8. A tunnel lining subject to axial thrust during construction, comprising a plurality of rings, 55 each formed of a plurality of wrought metal segments, each segment being composed of a skin plate, side walls for the segment extending inwardly of said skin plate, end walls for the segment abutting the side walls and skin plate, and transverse members for the segments having plane, square-cut ends engaging said side walls to resist said thrust, the transverse members being so positioned in the segments that when the segments are disposed in successive rings, the 60 members of laterally adjacent segments are in substantial alinement, and form ribs axially of the tunnel, effective to remove the thrust load in part, at least, from the skin plates.

9. A tunnel liner segment comprising a substantially rectangular skin plate curved longitudinally, side walls for the segment, of equal depth and extending inwardly from the curved edges of the plate, and members extending transversely of the plate, having plane, square-cut ends abutting the 70 side walls, and so positioned in the segment that

when the segments are connected to form successive rings in a tunnel lining, the members in laterally adjacent segments are substantially in alinement and constitute axial ribs serving to transmit the axial thrust to which the lining is subjected, thereby relieving the skin plate, at least partially, of said thrust.

10. A tunnel lining segment comprising a skin plate and side walls of equal depth therefor, both side walls having means equally spaced from the plate projecting inwardly thereof to increase the section modulus of the segment, and to resist transverse deflection of the side walls between points of attachment when two segments are secured together side by side, said plate, walls, and the modulus-increasing means of both the latter 80 85 90 constituting a unitary structure.

11. A tunnel lining comprising juxtaposed rings formed of segments, each segment including a skin plate, side walls, and angularly disposed, 95 longitudinally extending reinforcement for said walls, said reinforcement, the side walls and edges of the plates of adjacent segments constituting a circumferential inwardly projecting rib of I-section between adjacent rings.

12. A tunnel liner segment comprising a substantially rectangular, longitudinally curved, skin plate, side walls therefor of substantially equal depth extending inwardly from the curved edges of the plate, and longitudinal reinforcement extending along the side walls parallel to the skin plate and inwardly of the side walls, from points thereon spaced substantially equally from the plate.

13. A tunnel liner segment comprising a rectangular plate curved in one direction, side walls of substantially equal depth for the plate, extending inwardly of the curved edges thereof at right angles thereto, and longitudinal reinforcements for said walls extending therealong and inwardly thereof at right angles thereto, the reinforcements of both walls being spaced the same distance from the plate.

14. A tunnel liner segment comprising a curved skin plate, side walls of substantially equal depth extending inwardly at substantially right angles to the skin plate, and angle irons secured to the side walls adjacent the inner edges of the latter, said angle irons having one flange engaging the side walls and the other flange extending inwardly thereof parallel to the skin plate, and spaced substantially the same distance from the skin plate.

15. A tunnel liner segment comprising a substantially rectangular skin plate curved in one direction, side walls extending laterally from the curved sides of said plate, and end walls secured to the ends of said skin plate and side walls, said end walls having a cutout portion adjacent their inner edge.

16. A tunnel liner segment comprising a back of wrought plate metal bent to substantially the form of an arc of a circle and constituting the lining portion, side walls of wrought metal of substantially equal depth, extending inwardly from the back and extending substantially the entire length thereof so that when the plates are assembled in end-to-end relation the side walls constitute substantially continuously extending, inwardly disposed supporting ribs, and wrought metal reinforcing portions extending inwardly at an angle to such walls adjacent their inner edges and substantially equally spaced from the back, and being of such form and dimensions as to prevent the ribs from buckling.

17. A tunnel liner segment comprising a skin plate, side walls therefor, longitudinal reinforcing means for both said walls disposed at an angle thereto and effective to resist transverse deflection of the side walls of adjacent segments between points of attachment when secured together, the reinforcing means for at least one of said side walls extending inwardly thereof, the side walls and reinforcing means of adjacent connected segments together with the edges of the skin plates forming parts thereof, constituting an inwardly projecting flanged rib between said adjacent connected segments. 10
18. A tunnel liner segment comprising a skin plate, side walls therefor, longitudinal reinforcing means for both said walls disposed at an angle thereto and effective to resist transverse deflection of the side walls of adjacent segments between points of attachment when secured together, the reinforcing means for at least one of said side walls extending inwardly thereof, the side walls and reinforcing means of adjacent connected segments together with the edges of the skin plates forming parts thereof, constituting an inwardly projecting flanged rib between said adjacent connected segments, and transverse thrust members extending across the skin plate and engaging the side walls, said members being of such size as to be capable of carrying the major portion of the load axially of the tunnel to which the segment may be subjected. 20
19. A tunnel liner segment comprising a skin plate, side walls therefor, longitudinal reinforcing means for both said walls disposed at an angle thereto and effective to resist transverse deflection of the side walls of adjacent segments between points of attachment when secured together, the reinforcing means for at least one of said side walls extending inwardly thereof, the side walls and reinforcing means of adjacent connected segments together with the edges of the skin plates forming parts thereof, constituting an inwardly projecting flanged rib between said adjacent connected segments, and end plates secured to the skin plate and side walls. 30
20. In a tunnel liner segment, a plate having its edge portions bent up to form side walls of equal depth, and reinforcing bars attached to the inside surfaces of said side walls adjacent their edges and equally spaced from the body of the plate, said bars having a dimension ra- 50
- dially of the segment less than the depth of said walls. 60
21. A tunnel lining segment comprising a plate having its edge portions bent up to form side walls, the curved portion at the junction of the side walls and the plate being offset from the plane of the latter, and longitudinal reinforcing members attached to said side walls adjacent their edges. 80
22. A tunnel lining segment comprising a skin plate and side walls of equal depth therefor, both side walls having means equally spaced from the plate projecting inwardly thereof to increase the section modulus of the segment, said plate, walls, and the modulus-increasing means of both the latter constituting a unitary structure, and to resist transverse deflection of the side walls between points of attachment when two segments are secured together side by side, the aforementioned unitary structure having a longitudinal recess adjacent the edge of one of the side walls forming caulking grooves accessible from the interior of the lining when the segments are placed side by side. 90
23. A tunnel lining segment comprising a plate having its edge portions bent up to form side walls, the curved portion at the junction of the side walls and the plate being offset from the plane of the latter, longitudinal reinforcing members attached to said side walls adjacent their edges, and a longitudinal recess adjacent the edge of one of said side walls adapted to form a caulking groove when segments are disposed side by side in a tunnel lining. 95
24. A tunnel liner segment comprising a skin plate, side walls therefore, longitudinal reinforcing means for both said walls disposed at an angle thereto and effective to resist transverse deflection of the side walls of adjacent segments between points of attachment when secured together, the reinforcing means for at least one of said side walls extending inwardly thereof, the side walls and reinforcing means of adjacent connected segments together with the edges of the skin plates forming parts thereof, constituting an inwardly projecting flanged rib between said adjacent connected segments, and plates secured to the skin plate and side walls, and a recess adjacent the edge of at least one of the end walls, adapted to form a caulking groove when segments are disposed end to end. 110
